UNITED STATES PATENT OFFICE.

ALVA R. McCLELLAND, OF CLINTON, MISSOURI.

MAIL-BOX.

SPECIFICATION forming part of Letters Patent No. 731,804, dated June 23, 1903.

Application filed November 22, 1902. Serial No. 132,498. (No model.)

To all whom it may concern:

Be it known that I, ALVA R. McCLELLAND, a citizen of the United States of America, residing at Clinton, in the county of Henry, State of Missouri, have invented a new and useful Mail-Box to be Used on Rural Delivery Routes, of which the following is a specification.

My invention relates to rural mail-boxes; and the same is to design an absolutely weather-tight mail-box of simple construction which will act automatically and be so easily operated that the "route-man" may easily deposit mail without even stopping his horse and that even a child who can but reach the bottom of the box may take mail therefrom with perfect ease and safety.

The simple and unique construction employed by me in carrying out my invention is fully described in this specification and claimed, and illustrated in the accompanying drawings, forming a part thereof, in which—

Figure 1 is a perspective of my mail-box when open at the side. Fig. 2 is a vertical transverse section of the same when in a closed position. Fig. 3 is the head of the outer cylinder or mail-receptacle. Fig. 4 is a sectional view showing the head of the inner cylinder or cover.

Like numerals of reference designate like parts in the different views of the drawings.

The numeral 1 designates a cylinder having heads 2, a convex body 3, and a support 4.

The numeral 5 designates a cylinder having heads 6 and a convex body 7.

The convex body 3 is constructed of sheet metal and covers about one-half of the cylinder 1. Heads 2 are preferably metal or cast, having outwardly-extending flanges, to which the body 3 is riveted. At the center of head 2 is a hole 8, and near the circumference of same are holes 9 and 10. The convex body 7 is constructed of sheet metal, which covers about five-sixths of cylinder 5. Heads 6 have inwardly-extending flanges, to which the body 7 is riveted. At the center of heads 6 is a hole 11, and at the circumference a slight indentation 12.

13 is a metal weight fastened securely to head 6 at a point opposite the open side of the cylinder 5.

In mounting cylinders 1 and 5 a bolt or shaft

14 extends through the posts 15, (or any convenient means by which the box may be suspended,) through the openings 8 in the heads 2, and the openings 11 in the heads 6, the inner cylinder 5 being slightly shorter and slightly less in circumference than the outer cylinder 1. The bolt or shaft 14 also extends through two thin metal washers 16, which are placed between the heads 6 of the inner cylinder 5 and the heads 2 of the outer cylinder to prevent friction. The inner cylinder 5, which forms the mail-receptacle or mail-box proper, can now be easily turned, so that the open side 65 will be down or at the side, and when allowed to assume its normal condition it will automatically turn to the position shown in Fig. 2—viz., with the open side up.

4 is an iron rod, with shoulders which fit 70 against the heads 2, and which is riveted or otherwise fastened to heads 2 at the points 10.

18' is a small cylindrical metal weight which slides upon rod 4 from 10 to 10 and which when at the center of 4, as in Fig. 1, 75 indicates the presence of mail and is a signal to route-man. This rod and weight also serve to balance the outer cylinder and retain it with its open side down. When not in use as a signal, it may be moved out to point 10. 80

To lock my mail-box any ordinary padlock or spring-lock may be inserted in opening 9 of head 2, which opening 9 is when box is in a closed position opposite depression 12 in the head 6 of the inner cylinder. The lock in passing through 9 will fit into 12, so as to prevent the cylinders from revolving, and thus bringing the open sides together.

Instead of weight 13 in head 6 head 6 may be made heavier on the lower than on the 90 upper side of this circular end. Also head 2 may be made heavier at the lower than the upper side—viz., at 17 heavier than at 18.

I do not wish to be limited as to details of construction, as these may be modified in 95 many particulars without departing from the spirit of my invention.

Having described my invention, what I claim as new, and desire to secure by Letters Patent, is—

1. In a mail-box, the combination of two open-sided cylinders pivoted to revolve one within the other, a weight on the open side of the outer cylinder and a weight on the closed

side of the inner cylinder, said weights adapted to bring the said cylinders automatically into position to close the box.

2. In a mail-box, the combination of two cylinders, pivoted to revolve one within the other, a brace-rod extending between the ends of the outer cylinder, a signal mounted to slide longitudinally on the brace-rod, said rod and signal being adapted to serve as a weight to balance the outer cylinder.
3. In a mail-box, the combination of two

cylinders pivoted to revolve one within the other, the head of the inner cylinder having a depression 12, and the head of the outer cylinder having an opening 9, said depression and opening being adapted to receive a lock, whereby the box is locked in a closed position. 15
